COMBINATION HEATER AND DEFROSTER

Carl H. Will and Henry W. Fink, Minneapolis,
Minn., assignors to Tropic-Aire, Incorporated,
Minneapolis, Minn., a corporation of Delaware

Application September 7, 1937, Serial No. 162,706

4 Claims. (Cl. 257—137)

This invention relates to new and useful improvements in combination heaters and defrosters and more particularly to an apparatus of the general character disclosed in their pending 5 application, Serial No. 137,842, filed April 19, 1937.

An object of the present invention is to provide a combination heater and defroster including a casing having a main air outlet and 10 an auxiliary air outlet adapted to be connected to a defrosting device, and a combination fan and blower being mounted adjacent one side of the core adapted to draw air through the core and discharge it from said main and auxiliary 15 air outlets.

Other objects of the invention reside in the unique construction of the air circulating means, which comprises a fan and blower adapted for simultaneous operation; in the provision of an 20 eccentrically disposed or spiral shaped air passage, communicating directly with the auxiliary air outlet and a portion of the air circulating ducts of the heater; in the construction of a blower mounted within said eccentrically disposed air passage for drawing air through a portion of the core and discharging it from the 25 heater through the auxiliary air outlet; in the general construction of the annular member secured in position at the discharge side of the core and in which the fan is mounted; and, in the provision of a blower secured directly to 30 said fan and adapted for simultaneous rotation therewith, to draw air through a portion of the core and discharge it from the heater through 35 said auxiliary air opening.

Other objects of the invention will appear from the following description and accompanying drawings and will be pointed out in the annexed claims.

40 In the accompanying drawings there has been disclosed a structure designed to carry out the various objects of the invention, but it is to be understood that the invention is not confined to the exact features shown as various changes 45 may be made within the scope of the claims which follow.

In the drawings:

Figure 1 is a vertical sectional view on the line 1—1 of Figure 2, showing the general construction of the heater;

Figure 2 is a sectional view on the line 2—2 of Figure 1, showing the arrangement of the auxiliary air outlet; and

Figure 3 is a detail sectional view on the line 55 3—3 of Figure 2.

The novel heater, herein disclosed, comprises a casing 2 composed of front and rear casing sections 2^a and 2^b, the section 2^b being provided at its rear with suitable air intake openings 3, and the front section 2^a having a main air outlet opening 4 in its front wall, as best illustrated in Figures 1 and 2. An annular frame 5 is shown mounted for rotary adjustment in the opening 4, and has a plurality of deflectors 6 for controlling air circulation from the heater. A suitable screen 7 is preferably provided back of the deflectors 6, as best illustrated in Figure 1.

A suitable air heating core, generally indicated by the numeral 8, is suitably mounted within the casing 2 and comprises upper and lower 15 tanks 9 and 11, respectively, which communicate with the usual water circulating tubes 12 and an inner tank 13. The usual water intake and discharge pipes 14 and 15 are shown connected to the tanks 11 and 9, respectively, of the core, 20 and have their free ends projecting from the heater whereby they may be suitably connected to the fluid cooling system of the vehicle engine, by suitable conduits, not shown. The core is shown provided with a central opening 16. 25

A feature of the present invention resides in the specific construction of the means provided for circulating air through the core and casing. As best shown in Figure 1, an annular member 17, having a cone-shaped portion 18, is mounted 30 in fixed relation to the core 8, and has its inwardly facing edge positioned in close proximity to the core, as illustrated in Figure 1. The annular member 17 may be supported in position by suitable rivets 19 secured to lugs 21 provided 35 on a spacing member 22, which is secured to the core by suitable means, not shown.

Suitable housing members 24 and 25 are secured together as shown at 26, in Figure 1, and cooperate with a portion of the annular member 17, to provide a spiral shaped or eccentrically disposed air passage 27. The air passage 27 substantially surrounds the cylindrical portion of the member 17, and communicates with the air outlet 28, as best shown in Figure 2. By reference to Figure 1, it will be noted that an annular gap 30 is provided between the inner edge 20 of the spacing member 22, and the periphery of the member 17, through which air may be 45 drawn through the outer portion of the core and into the air passage 27, which communicates with the auxiliary air outlet 28.

A suitable blower 29 is mounted in the chamber 27 and comprises an annular rim 31, shown 55

secured to the outer terminals of the blades of a suitable air impeller or fan 32, in such manner that the blower 29 will rotate in the spiral passage 27, whereupon the fan 32 will rotate within the opening provided by the annular member 17, as clearly illustrated in Figures 1 and 2.

The fan 32 and blower 29 are located in front of the core, adjacent to the screen 7, and are driven by a suitable motor 33, mounted in the central opening 16 of the core.

Referring now to Figure 1 it is again noted that the outer casing 2 is composed of a front section 2^a, and rear section 2^b. The section 2^a carries an annulus 2^c which is cross-sectionally L-shaped, to provide a part 2^d which fits the inner surface of the rear section 2^b, and a part 2^e which engages the outer face of the blower housing or front section 24 thereof, to hold the blower housing and radiator against forward axial movement. The annulus 22 has an outwardly extending flange 22^a which with the shroud, or annulus 17, defines the annular gap 30. The section 25 also has an opening defined by an inturned flange 25^a, which flange is fitted over the flange 22^a as shown to center the housing on the ring 22. The element 2^c is attached to the forward outer casing section 2^a so that this element is removable with that section. The means for securing the part 2^d to the rear outer casing section 2^b have not been shown, but screws can be used like those shown in co-pending application 162,705 of Fink, for detachably securing 2^c to 2^b. When this detachable securing means is loosened the front section 2^a can be removed and with it the annulus 2^c thus permitting forward axial movement of the blower housing.

Section 25 may or may not be rigidly secured to the ring 22. If it is so secured then after bolts 26 have been removed the section 24 can be removed after section 2^a and its ring 2^c have been removed. If it is not secured then the entire blower housing with its fan can be removed after the fan is disconnected from the motor shaft and after section 2^a is removed.

The pipes 14 and 15 traverse and are supported in the back wall of the rear casing section 2^b by resilient cushion inserts or gaskets respectively designated 14^a and 14^b. It is noted that each pipe, at a point adjacent the corresponding insert is bent so that its long axis is at right angles to the axis of that part of the pipe which passes through the insert.

By constructing the air circulating means, as herein disclosed, and locating the fan and blower at the front of the core, air is drawn through the core, and not blown therethrough, as in the structure disclosed in pending application, Serial Number 137,842, hereinbefore mentioned. It will also be noted that the fan 32 will circulate air through the main outlet opening 4 of the casing, and the blower 29 will draw air into the spiral air passage 27 and discharge it through the auxiliary outlet 28. The air circulated from the heater through the auxiliary passage 28, is drawn through the outer portion of the core, whereas the warm air discharged from the heater through the main air outlet 4, is drawn through the intermediate or central portion of the core.

The heater, as illustrated in Figures 1 and 2, is comparatively simple and inexpensive in construction. Because of the annular air gap 33 provided between the periphery of the member 17 and the inner edge 20 of the member 22, warm air is drawn into the spiral air passage 27 by the blower 29, which air is discharged through the

air outlet 28. A suitable conduit, not shown, may be connected to the auxiliary discharge 28 for conducting warm air therefrom to a suitable defroster device. The deflectors 6 provide means whereby the circulation of warm air from the heater may readily be controlled.

We claim as our invention:

1. A heater of the class described, comprising a first casing having a first discharge opening, a radiator in the casing having a face opposed to said discharge opening, a second casing within the first casing interposed between the face of the radiator and said first discharge opening, a first annulus attaching the second casing to the radiator, said first annulus and said second casing having means by which one is detachably centered on the other, a second annulus within the first annulus and within the second casing and dividing said second casing into an outer chamber communicating with the radiator through said first annulus, and an inner passage establishing communication between the radiator and said first discharge opening, a second discharge opening leading tangentially from the outer chamber of said second casing and through said outer casing, and fans within the second casing respectively for forcing air out of said first opening and for drawing air into the outer chamber of said second casing, and forcing it through said second opening. 30

2. A heater of the class described, comprising a first casing having a first discharge opening, a radiator in the casing having a face opposed to said discharge opening, a second casing within the first casing interposed between the face of the radiator and said first discharge opening, a first annulus attaching the second casing to the radiator, said first annulus and said second casing having means by which one is detachably centered on the other, a second annulus within the first annulus and within the second casing and dividing said second casing into an outer chamber communicating with the radiator through said first annulus, and an inner passage establishing communication between the radiator and said first discharge opening, a second discharge opening leading tangentially from the outer chamber of said second casing and through said outer casing, and fans within the second casing respectively for forcing air out of said first opening and for drawing air into the outer chamber of said second casing, and forcing it through said second opening, one fan being mounted upon the other. 45

3. In a heater of the class described, a first casing having an air discharge opening, a radiator in the casing through which air moves toward said discharge opening, a second casing within the first casing, a shroud in part defining within the second casing, a central passage and a circumscribing chamber, both communicating with the radiator, a fan forcing air through the central chamber, a second fan in the circumscribing chamber, a motor operating the fans, and an annulus connecting one side of the second casing to the radiator, said annulus and said second casing having means by which one is centered on the other, said means in part defining with the shroud an annular passage through which air enters said circumscribing chamber. 70

4. In a heater of the class described, a first casing comprising separable front and rear sections, the front section having an air discharge opening, a radiator in the casing through which air moves toward said discharge opening, a sec- 75

ond casing as a fan housing within the first casing, said second casing comprising two separable parts, an annulus connecting one side of the second casing to the radiator, said annulus and said second casing having means by which one is centered on the other, said means in part defining a passage through which air enters

said second casing, and means carried by the front section of the first casing for holding said second casing against forward motion in an axial direction.
